Primary Examiner — Lauren D McVey

(57) **CLAIM**

The ornamental design for a cutting machine as shown and described.

DESCRIPTION

FIG. 1 is a perspective view of a cutting machine showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the cutting machine where the cutting machine is in a configuration of use.

The broken lines immediately adjacent to the claimed areas, and contain additional broken line subject matter, depict the bounds of the claimed design, while all other broken lines are directed to environment. The broken lines form no part of the claimed design.

1 Claim, 9 Drawing Sheets
